T. BRABSON ET AL.

FAUCET ADAPTED TO A FILTER

Filed April 27, 1921

UNITED STATES PATENT OFFICE.

TOM BRABSON, OF BROOKLYN, AND ERNEST FURST, OF NEW YORK, N. Y.

FAUCET ADAPTED TO A FILTER.

Application filed April 27, 1921. Serial No. 465,043.

To all whom it may concern:

Be it known that we, TOM BRABSON and ERNEST FURST, citizens of the United States, and residents, respectively, of the borough of

5 Brooklyn, in the county of Kings and State of New York, and the borough of Manhattan, county of New York, and State of New York, have jointly invented certain new and useful Improvements in a Faucet Adapted

10 to a Filter, of which the following is a specification.

This invention relates to a faucet adapted to a filter. Its object is the production of such a device whereby a user may draw a 15 fluid through the faucet without being filtered, or he may in turn cause the fluid to flow through the body of the faucet and thence through the filter. The outlet of the filter is closed during the discharge of the 20 fluid through the faucet, and the outlet for the faucet is closed during the discharge of the fluid through the filter, or the fluid may be discharged through the outlet of the filter and faucet at the same time.

25 Fig. 1 represents a part elevation and part axial vertical section of an exemplification of the faucet and the filter; Fig. 2 shows a section of Fig. 1 on the line 2, 2; Fig. 3 is a section of Fig. 2 on the line 3, 3; Fig. 4 represents an enlarged section of Fig. 2 on the line 4, 4; Fig. 5 indicates a section of Fig. 2 on the line 5, 5; Fig. 6 shows a section of Fig. 2 on the line 6, 6 and Fig. 7 shows a section of Fig. 2 on the line 7, 7.

35 A water supply pipe 18 has connected thereto a faucet A, which latter comprises the body portion 20 having the inlet port 21, the exteriorly threaded end 22 and the valve chamber 23. The said chamber is formed 40 by the wall 24 having the interior thread 25 at its upper end and the depending guide sleeve 26 at its lower end. A valve seat 27 is formed at the upper end of the sleeve 26. An outlet nozzle 30 has formed therewith

45 the head 31 and from the latter extends the tubular threaded shank 32, with the cross ports 33 connecting with the axial inlet port 35. Cross ports 36 are formed in the upper end of the nozzle 30, and a portion of said 50 nozzle is flattened at its lower end as indi-

cated at 37. An operating handle 38 with the operating lugs 39 has a D-shaped opening 40 which engages the lower end of the nozzle 30. A screw 41 is in threaded engagement with an opening in one of the lugs 55 39 and grips the nozzle 30. An annular packing ring 43 is secured to the lower face of the head 31 and can bear on the valve seat 27.

A cap is indicated in its entirety by the letter B and is shown to comprise an upper chamber 50 and a lower chamber 51. From the chamber 50 extends the upper sleeve 53 with the interior thread 54 and the exterior thread 55. A cap nut 56 is in threaded engagement with the exterior thread 55 and packing 57 is interposed between said nut and the cap B. With the said cap is formed the lower sleeve 59 with the exterior thread 60 and the interior thread 61. A valve seat 65 70 is formed at the upper end of the sleeve 59 for its axial port 66.

An indicator arm 67 extends up from the cap B. The threads 60 of the cap B engage the threads 25 of the wall 24.

75 A filter is indicated in its entirety by the letter C and comprises a barrel 70 with the bottom wall 71 and the open top end 72. A handle 73 extends from the barrel 70. A spindle 75 has formed therewith the threads 80 76 and 77 at its upper portion and at its lower portion is formed a sleeve 78, that extends from and is formed with the bottom wall 71 of the barrel 70. The sleeve 78 has formed therewith the threads 79 and a pointer 80 extends from the wall 71. The sleeve 78 has the bottom wall 81 and has formed therein the upper cross ports 82 and lower cross ports 83 which connect with its axial port 85. Longitudinal ports 86 are 85 formed on the lower outer face of the sleeve 78 and connect with the ports 83. The threads 79 of the sleeve 78 are in engagement with the threads 54 of the sleeve 53 of the cap B. The wall 81 is dovetailed for a 90 valve 87 preferably of flexible material, that can be made to bear on the valve seat 65.

A cage with the side wall 90, top wall 91 and bottom wall 92 encircles the spindle 75 and the upper portion of the sleeve 78. 100

Openings 94 are formed in wall 90. A cylindrical shaped filtering material 96 with the bottom wall 97 and the top wall 98 covers the said cage. A threaded cap 100 with the operating lugs 101 is in threaded engagement with the threads 76 and bears down on the top wall 91 and side walls 90, of said filtering material. A cap 105 with the outlet nozzle 106 engages the top end of the barrel 70. A cap nut 108 with the operating bars 109 is in threaded engagement with the threads 77 and bears on the roof of the cap 105.

To operate the device and in case water is to be drawn through the faucet A and outlet nozzle 30 without entering the filter C, the valve 87 is maintained on the valve seat 65, and none of the water from the faucet A can flow through the axial port 66 into said filter C. The operator turns the nozzle 30 by means of the operating lugs 39, whereby the said nozzle 30 is raised by the coaction of the tubular threaded shank 32 with the interior threads 61 of the cap B. The head 31 with the packing ring 43 will rise with the cross ports 36 and water will flow from the supply pipe 18 through the inlet port 21, through the ports 36 and be discharged from the outlet nozzle 30.

In case water is to be drawn through the filter C the nozzle 30 is turned to seat the packing ring 43 on the valve seat 27, so that no water can issue through the nozzle 30, and the operator turns the barrel 70 by means of the handle 73. By this means the valve 87 is raised from the valve seat 65. By this disposition of ports water flows from the pipe 18, through the port 21. Thence through the cross ports 33 into the axial port 35, through the longitudinal ports 86, then through the ports 83, into the axial port 85 on its way through the cross ports 82 of the sleeve 78. The water now enters the cage having the side wall 90 and is discharged therefrom through the openings 94 and thence through the filtering material into the barrel 70. From the latter it is discharged through the outlet nozzle 106.

The water may flow simultaneously through the nozzle 30 and through the filter C, by keeping the packing ring 43 above the valve seat 27 and maintaining the valve 87 above the valve seat 65.

Having described our invention what we desire to secure by Letters Patent and claim is:

1. In a device of the character described the combination of a body portion with an inlet port, a valve chamber extending from said body portion and connecting with said port, a cap with an axial port for said chamber, an outlet nozzle with ports cooperating with said chamber, means to actuate the nozzle, to open and close communication between

said chamber and nozzle, a sleeve with a port in engagement with said cap and normally closing said axial port and means to actuate said sleeve and open said port to cause a flow of fluid through the sleeve.

2. In a device of the character described the combination of a body portion with an inlet port, a valve chamber extending from said body portion and connecting with said inlet port, a cap with an axial port for said chamber and having a tubular extension comprising a sleeve, a valve seat at the upper end of the axial port, an outlet nozzle for said chamber extending through one end thereof, means to actuate the outlet nozzle to cause a flow of fluid from the inlet port through said nozzle, a sleeve with a bottom wall and ports at its lower end extending through said tubular extension, a valve for said bottom wall normally engaging the valve seat of the axial port of the cap, and means to actuate said sleeve and withdraw the valve from its seat and to cause a flow of fluid from said inlet port through said sleeve.

3. In a device of the character described the combination of a body portion with an inlet port, a valve chamber extending from the body portion and connecting with said port, a valve seat in said chamber, an outlet nozzle having a head coacting with said valve seat, a cap with an axial port for the valve chamber and having a valve seat formed at the upper end of its axial port, a sleeve with a bottom wall in threaded engagement with said cap having ports at its lower end and a valve in its bottom wall coacting with the valve seat of the axial port of the cap.

4. In a device of the character described the combination in a faucet of a body portion with an axial port, a wall extending from the body portion forming a valve chamber connecting with said port, a guide sleeve extending from said chamber and having a valve seat formed at the upper end thereof, an outlet nozzle located in said guide sleeve having a head at its upper end and ports below said head, a tubular threaded shank extending from the head and a cap for the valve chamber having interior threads engaging said threaded shank.

5. In a device of the character described the combination of a body portion with an inlet port, a wall extending from the body portion forming a valve chamber, a cap for the valve chamber having an axial port and having an interior thread at its lower end and an interior thread at its upper end, a valve seat formed at the upper end of the axial port of the cap, a tubular threaded shank with cross ports in engagement with the threads at the lower end of the cap, an outlet nozzle with cross ports extending from

said threaded shank, a sleeve with a bottom wall and with cross ports at its upper end and exterior threads at its lower end, the latter threads engaging the threads at the upper end of said cap, cross ports at the lower end of the sleeve, longitudinal ports in the threads at the lower end of the sleeve connecting with the cross ports at the lower end of the valve and a valve con-

nected to the bottom wall of the sleeve co-¹⁰ acting with the valve seat of the axial port of the cap.

Signed at the borough of Manhattan in the county of New York and State of New York this 19th day of April A. D. 1921.

TOM BRABSON.
ERNEST FURST.
